CHECK SYMBOL APPARATUS

Marcel Linsman, Liege, Belgium, assignor to International Standard Electric Corporation, New York, N.Y., a corporation of Delaware

Application January 28, 1955, Serial No. 484,715

Claims priority, application Netherlands April 2, 1954

3 Claims. (Cl. 235—153)

The invention relates to calculating means and more particularly to means for verifying that a group of associated symbols such as a decimal number, has not suffered a transposition of two symbols while being transcribed manually or otherwise. For example, when keying a number on a machine, apart from a single wrong digit, a transposition of two digits has been found to be the most frequent error, e.g. 27 is keyed instead of 72, or 237 instead of 732.

Among the recent work on this subject, the Belgian Patent No. 501,525 describes the use of a proof symbol to be permanently associated with each group and such that it is a linear function of the normal symbols forming the group. To avoid a large number of different proof symbols the following type of function is used:

$$\sum_{i=1}^{i=n} b_i a_i \pmod{p} \quad (1)$$

where a_i ($1 \leq i \leq n$) is a set of associated numerical symbols such as those forming a decimal number, b_i ($1 \leq i \leq n$) is one of a group of predetermined fixed integer coefficients and each characteristic of the position of a symbol in the group, n is the number of symbols and p is a predetermined fixed integer used as a modulus so as to limit the number of different possible values of the function to p . For example, if the coefficients b_i ($1 \leq i \leq 6$) are respectively equal to 1, 2, 3, 4, 5, 6 for the digits of six-digit decimal numbers, starting from left to right, and if $p=11$, the proof symbol for 278498 will be given by

$$1(2)+2(7)+3(8)+4(4)+5(9)+6(8)=149 \equiv 6 \pmod{11} \quad (2)$$

In other words, 6 is the remainder after dividing 149 by 11. Thus, the number with its proof symbol can, for example, be written as 278498-6 by putting the proof symbol on the right. Then whenever the number is transcribed and there are possibilities of errors, the function (1) can be computed from the transcribed digits and checked against the transcribed proof digit.

For the function given by (1) a transposition of two symbols of different values a_i and a_j will produce an error which should be different from 0 ($\pmod{p}$) in order to be detected, i.e.

$$(b_i - b_j)(a_i - a_j) \not\equiv 0 \pmod{p} \quad (3)$$

This means that for ranks between which a single transposition of two symbols should be detected, the respective coefficients b_i and b_j for these ranks should be such that (3) will be satisfied, irrespective of the values of a_i and a_j .

As mentioned above, the other most frequent error is a single wrong digit, and in such a case the corresponding change of the function given by (1) should also be different from 0 ($\pmod{p}$), i.e.

$$b_i(a_i - a'_i) \not\equiv 0 \pmod{p} \quad (4)$$

in which a'_i is the wrong value of a_i .

2

The succession of coefficients b_i may take various forms other than that given in the above example, as will be explained later. Also various values of p are possible, some giving better results than others.

5 It is readily recognized that for decimal numbers a value of 11 for p is most suitable since

$$a_i - a_j \not\equiv 0 \pmod{11} \quad (5)$$

and in such a case the coefficients b_i ($\pmod{p}$) should be chosen so that they all differ from one another if any single transposition of two digits has to be detected, and further, none of these coefficients should be equal to 0 ($\pmod{p}$) if (4) is to be satisfied, i.e. if any single digital error should also be detected. A value of 10 for p would also satisfy (5), but since $10=2 \times 5$, (3) and (4) could only be satisfied in certain cases, whatever coefficients b_i are chosen. On the other hand, it is desirable to take the lowest possible value for p in order to limit the number of the different proof symbols, and also, since the function given by (1) is such that in order to calculate it, it will at least be necessary to record p different symbols and the necessary recording equipment will increase as p increases.

Apart from transpositions between any two digits of a number, there remains the possibility of a transposition between a normal digit and the proof symbol. This may be just as likely to happen as an ordinary transposition, especially if the ordinary digits are also used for the proof symbols and, moreover, if it is possible to use the same keys for typing the proof digit as those used for typing the other digits. Some considerations on a possible transposition between the proof symbol and one of the ordinary symbols are given in the Belgian patent mentioned above, but the proof symbol is treated as a special case distinct from the other symbols.

This is not necessary, and if the proof symbol is treated exactly in the same way as the other symbols, it becomes implicitly determined from

$$F = \sum_{i=0}^{i=n} b_i a_i \pmod{p} \quad (6)$$

where F (the proof symbol) is a predetermined fixed integer, e.g. 0, p is equal to $n+1$, and since the $n+1$ coefficients b_i form a set of predetermined integer coefficients which include a coefficient for the proof symbol also. All these coefficients can be predetermined at will, bearing in mind the restrictions given above in relation to (3) and (4). Thus it is clear that in the case of $p=11$, it is possible to choose a group of ten different coefficients, numbered 1, 2, . . . 9, 10, such that any single transposition of two digits (whether it includes the proof symbol or not) as well as any single wrong digit for a ten-digit number (including the proof symbol) can be detected, one of the ten coefficients being assigned to the proof symbol associated with the number.

In order to be able to detect such errors as mentioned above, any decimal number to be keyed should have a proof symbol permanently associated with it at all times when such errors can occur. As each digit a_i of such a number would be keyed into a machine, this machine would compute the partial function:

$$b_i a_i \pmod{p} \quad (7)$$

and when all digits including the proof symbol would have been keyed, the sum of these partial functions would be obtained so as to derive the check symbol F by taking the remainder of the division of the sum by p . If F is not obtained, a keying error has been made, such as those mentioned above. This means that for each of the digits

to be keyed, different coefficients b_i must be chosen in accordance with the rank, and a device which can be termed a rank selector can be used, as in the said Belgian patent, to obtain the correct function (7) in accordance with the value of the digit and its rank. If the keying of numbers having a different number of digits is to be considered, the rank selector will have to make a total number of steps which varies as the number of the digits varies. In one case the rank selector would be left in one position after the keying of a number, while in another case it would be in another position after the keying of another number having another number of digits, which means that the rank selector would have to be restored to normal after the keying of every number and would require as many positions as the maximum number of digits forming a number.

In the Belgian patent mentioned above, it has been mentioned that the coefficients b_i can be chosen in such a way that they satisfy the relation

$$b_i \equiv rb_{i+1} \pmod{p} \quad (8)$$

where r is also a fixed predetermined integer. In other words, the coefficients form a geometric progression of common ratio r such as

$$6^0, 6^1, 6^2, 6^3, 6^4, 6^5, 6^6, 6^7, 6^8, 6^9 \quad (9)$$

where r is equal to 6, or

$$1, 6, 3, 7, 9, 10, 5, 8, 4, 2 \quad (10)$$

when the residues with respect to 11 used as a modulus are taken. By this means it becomes possible to use a rank selector which has a certain number of different positions but which is closed on itself, so that after the keying of a number having an arbitrary number of digits, the rank selector will be left in some arbitrary position from which it can again be moved cyclically when the number is keyed. If F , in (6) which defines the proof symbol, is made equal to zero by a proper selection of coefficients b_i , then it is immaterial in which position the rank selector stands when a number is keyed, e.g. with $p=11$ and $r=6$ and with a set of coefficients b_i to be explained later, if the number 278498-8 is keyed when the rank selector stands in the position corresponding to $b_i=1$, then the calculated function F , using the coefficients b_i of (10), will be given by

$$1(2) + 6(7) + 3(8) + 7(4) + 9(9) + 10(8) + 5(8) = \\ 297 \equiv 0 \pmod{11} \quad (11)$$

but if this number is now keyed again starting with the rank selector now in the position corresponding to $b_i=8$, the function F will again be the same, i.e.

$$8(2) + 4(7) + 2(8) + 1(4) + 6(9) + 3(8) + 7(8) = \\ 198 \equiv 0 \pmod{11} \quad (12)$$

In the Belgian Patent No. 501,548, a rank selector is avoided altogether. An electro-mechanical relay recording device capable of occupying p distinct stable conditions is used and as each digit a_i is keyed, the recorder moves from its previous condition F_{i-1} to a new condition F_i in accordance with the predetermined relation

$$F_i \equiv (rF_{i-1} + a_i) \pmod{p} \quad (13)$$

If the recorder is originally in a predetermined condition, i.e. the zero condition, as the digits $a_0, a_1, \dots, a_{n-1}, a_n$ of a number are keyed, it will be moved to the conditions

$$a_0, (ra_0 + a_1) \pmod{p} \dots$$

$$\sum_{i=0}^{i=n-1} r^{n-i} a_i \pmod{p}, \sum_{i=0}^{i=n} r^{n-i} a_i \pmod{p}$$

which last condition is of the form given by (6). The computations, i.e. the changes of conditions for the recorder, are carried out in a static manner, in the sense that the recorder is not a cyclic counter, and by means of a matrix of suitably interconnected contacts.

In the Belgian Patent No. 503,715 a similar arrangement is used for the special case where $p=11$ and $r=10$. If one generalizes this example to the particular case of r being equal to $p-1$, the Relation 13 then becomes

$$F_i \equiv (a_i - F_{i-1}) \pmod{p} \quad (14)$$

For the sake of comparison it can be remarked that in case of the Belgian Patent No. 501,525 the relation corresponding to 13 and 14 is

$$F_i \equiv (F_{i-1} + b_i a_i) \pmod{p} \quad (15)$$

but a rank selector is necessary to choose the correct coefficient b_i and in this patent the recorder is a cyclic counter.

An object of the invention is to calculate a function F (the proof symbol) of the form given by (6) and where the coefficients $b_i (0 \leq i \leq n)$ are of the form given by (8), by using a recorder with p stable conditions in a novel and advantageous manner.

In accordance with a characteristic of the invention, as each numerical symbol, such as a_i , is keyed, the recorder moves from its previous condition F_{i-1} to a new condition F_i in accordance with the predetermined relation

$$F_i \equiv r(F_{i-1} + a_i) \pmod{p} \quad (16)$$

In this manner, as the digits $a_0, a_1, \dots, a_{n-1}, a_n$ of a number are keyed, the recorder will be successively moved to the condition $ra_0, r(ra_0 + a_1)$

$$30 \quad 30 \quad (mod. p) \dots \sum_{i=0}^{i=n-1} r^{n-i} a_i \pmod{p}, \sum_{i=0}^{i=n} r^{n-i} a_i \pmod{p}$$

which last condition is of the form given by (6).

In accordance with a further characteristic of the invention, a first and a second electrical ring counters both with p stable conditions, a first pulse source and a second pulse source having r times the frequency of the first one are provided, and upon the second ring counter being set in a condition a_i corresponding to the numerical symbol a_i while the first ring counter is in a condition F_{i-1} , the first and the second counter are both driven by the first pulse source until they respectively pass through the conditions 0 and $(F_{i-1} + a_i) \pmod{p}$ which 0-condition of the first counter causes a two-condition device to be displaced from its first to its second condition, thereby causing the second pulse source to drive the first counter while the second counter remains driven by the first pulse source until the first and second counters respectively reach their $r(F_{i-1} + a_i) \pmod{p}$ and 0-conditions which last condition, in conjunction with the two-condition device in its second condition, causes the disconnection of said pulse sources from said counters which remain in the conditions attained.

The above mentioned and other objects and characteristics of the invention will be better understood from the following description of an embodiment to be read in connection with the attached figure, which represents an electronic circuit permitting the checking of decimal numbers to determine if they have been correctly keyed, and which can also be used to determine which additional digit should be associated with the normal number in order to permit such a check.

Shown in the figure is the ring counter CT_1 which is represented as a rectangle divided into eleven squares each indicating a possible stable condition or stage of the counter. The stages are successively numbered from 1 to 9, 10, 0 which last stage is coupled back to the first stage 1 as shown. This counter will permit the finding of residues with respect to 11 used as a modulus of functions fed to it by way of pulses, the number of pulses characterizing the function. A lead is shown to be connected to all the stages of the counter and it is on this lead that the pulses will be applied, each pulse causing the counter to step from one condition to the next, e.g. from condition 5 to condition 6. As to counters which permit the achievement of this shift, reference is made

to the United States Patent No. 2,649,502, issued August 18, 1953, where a suitable counter using a cold cathode tube for each stage is described.

A second counter CT_2 , which can be of the same type as the first, also has eleven stable conditions or stages successively numbered from 10 to 2, 1, 0, which last stage is coupled back to the first stage 10 through a gate G_2 which is shown as a circle with the input and output leads in line and pointing towards the center of the circle. A control lead also pointing towards the center is used to apply potentials which will either block or unblock the gate. The open arrow at the end of the control lead is used to indicate that the gate G_2 is normally blocked. The reason for using the gate will appear later, but during most of the operations it will be unblocked, so that CT_2 will in effect be a ring counter, as is CT_1 . The closed arrow at the control leads of gates G_6 and G_8 indicate that these gates are normally unblocked and are blocked by a potential on the control lead.

A lead is also connected to all the stages of CT_2 and each pulse appearing at terminal P_1 connected to this lead will drive the counter CT_2 from one condition to the next. This terminal P_1 is connected to the output of a bistable electronic device BS_4 , e.g. a bistable multivibrator, represented by a rectangle divided into two squares 1 and 0 representing the two stable conditions. The device BS_4 is driven by the pulses appearing at the output of gate G_1 , which is of the same functional type as G_2 , and whose input is connected to terminal P_2 at which pulses of a suitable repetition frequency are constantly delivered. As represented, G_1 is normally blocked, but when it is unblocked, as will be explained later, BS_4 is continuously driven from one condition to the other and pulses appear at terminal P_1 , at half the frequency of those fed at terminal P_2 , to drive CT_2 . When gate G_3 , which is similar to gate G_2 , is unblocked, these pulses appearing at terminal P_1 are also applied to CT_1 . On the other hand, when gate G_4 , which is similar to gate G_2 , is unblocked, the pulses appearing at the output of G_1 will be applied to CT_1 .

Before continuing the description of the circuit, it will be assumed that the counter CT_1 is originally set in the arbitrary condition F_{i-1} ($0 \leq F_{i-1} \leq 10$) and that the counter CH_2 is set in its 0-condition. Immediately below, a table gives the sequential operations which occur from the moment that one of the ten digit keys (not shown) constituting a digit selector is depressed actuating a corresponding contact such as k_0 .

indicating that no keying error has been made and that one can proceed with keying the next number, while 1 is used to indicate the corresponding condition of a counter or of a bistable device, an unblocked gate or a closed make contact, or an O.K. signal. If digits of a number have already been keyed, the original condition F_{i-1} for counter CT_1 represents a sum (mod. 11) of partial functions of the type given by (7) e.g. if the first six digits of the number 278498-8 have already been keyed, the counter CT_1 is now in the

$$2(8) + 4(9) + 8(4) + 5(8) + 10(7) + 9(2) = 212 \equiv 3$$

(mod. 11)th condition, as will be understood from the operations which occur as a result of the depression and release of a digit key. Counter CT_2 is in the 0-condition due to previous keying. The additional horizontal lines in the 0-squares of the counters CT_1 and CT_2 indicate preferred conditions. In other words, when the circuit is placed in the operative condition, the start circuit should put these stages "on," e.g. the corresponding cold cathode tubes should be ionized.

The bistable devices BS_1 and BS_2 which are of the two-input (shown on the long sides of the rectangle) type are in the 0-condition. The gates G_4 and G_5 are unblocked and a signal is applied to the gate G_6 . Bistable device BS_3 should initially be in the 1-condition, except when an incorrect number has just been keyed. The notation 0/1 is therefore used. The gates G_1 , G_2 , G_3 and G_6 are blocked, while the gates G_7 and G_8 are blocked or unblocked depending on the conditions of BS_3 and CT_1 respectively. No O.K. signal is delivered, since this is controlled by a shift key (not shown) which should be operated only after a full number has been keyed. Contacts s and s' of this shift key appear on the figure.

Upon the operation of a digit key, such as K_8 , which is the check symbol for the number assumed, the various conditions of the elements will be as shown in the second row ($k=1$). Through the make contact, such as k_8 and the break contacts k_0 and k_8 , a suitable negative potential present at terminal P_3 will be applied to the corresponding stage, such as 8, of the counter CT_2 and through the corresponding decoupling means R_0 to the "1" inputs of the devices BS_1 , BS_2 and BS_3 which all move to their "1" conditions. Gate G_3 will now be unblocked, while gates G_4 and G_5 are blocked. Gates G_6 and G_7 are also unblocked. The potential at terminals P_3 is also applied to stage 0 of CT_2 and will be assumed to cause this stage to return to the "off" condition. If the counter

	CT_1	CT_2	BS_1	BS_2	BS_3	$G_{1/2}$	G_3	$G_{4/5}$	G_6	G_7	G_8	OK
$k=0$	F_{i-1}	0	0	0	0/1	0	0	1	0	0/1	0/1	0
$k=1$	F_{i-1}	0	1	1	1	0	1	0	1	1	0/1	0
$k=0$	F_{i-1}	a_i	1	0	1	1	1	0	1	1	0/1	0
$F_{i-1}+a_i \neq 11$	0	$\{ F_{i-1}+a_i \}$ mod. 11	0	0	1	1	0	1	1	1	0	0
$s=1$	$2\{ F_{i-1}+a_i \}$ mod. 11	0	0	1	0	0	0	1	0	1	1	0
$F_{i-1}+a_i = 11$	0	$2\{ F_{i-1}+a_i \}$ mod. 11	0	0	0	0	0	1	0	0	0	0
$s=1$	0	0	0	0	0	1	0	0	1	0	0	1

In this table, the first two columns refer to the states of the counters CT_1 and CT_2 respectively, the next three to the states of the bistable devices BS_1 , BS_2 and BS_3 , the next six to the states of the gates G_1 , G_2 , G_3 , G_4 , G_5 , G_6 , G_7 , and G_8 , and the last column to the potential at the O.K. terminal. As G_1 , G_2 and G_4 , G_5 are respectively controlled from the same points, one column for each pair is sufficient. The row $k=0$ indicates the initial conditions, when none of the keys are operated and the key contacts k_0 , k_1 . . . k_9 corresponding to the decimal digits 0, 9 . . . 1 are all in the break condition as shown. In the table, 0 is used to indicate the corresponding condition of a counter or of a bistable device, a blocked gate or an open make contact, or the absence of an O.K. signal,

65 CT_2 is realized by means of cold cathode tubes, one for each stage, as detailed in the United States Patent No. 2,649,502, this can occur by way of decreasing the anode potential of the tube forming the stage 0 to such an extent that this tube can no longer conduct and its anode-cathode gap is deionized.

On the other hand, to put the required stage in the "on" condition, the potential from terminal P_3 may be applied to the anode of the tube immediately before the one to be ionized. This will cause a momentary drop of potential at the anode of the preceding tube and when the digit key is released, the corresponding increase of potential at the anode will be transmitted via a capacitive coupling to the grid of the tube to be ionized. This tube, e.g. of

stage 8, will be ionized as BS_4 is always left in the 1-condition after the keying of a digit, for which condition the potential at terminal P_1 is sufficiently low to permit the ionization. As in the United States Patent No. 2,649,502 it can be assumed that terminal P_1 is commoned to all the cathode of the tubes forming the counter CT_2 .

The release of the digit key brings a state of affairs defined by the third row ($k=0$) of the table. BS_2 is driven in its 0-condition and as the gate G_6 conducts, the gates G_1 and G_2 are also made conductive. For the tube forming stage 10 of counter CT_2 , the grid should be coupled to the anode supply via a capacitive and resistive coupling identical to those between successive tubes. This is because it cannot be coupled to the anode of the tube forming stage 0 when the gate G_2 is blocked. Make contact k_0 should be connected to the point of this special coupling corresponding to a fictitious anode, so that the tube corresponding to stage 10 will be fired by the closure and opening of contact k_0 in the same conditions as the others. Since the cathodes of the tubes are commoned, the counter CT_2 can be designed to permit only the ionization of a single tube at a time. Then, as soon as the correct tube has been ionized in response to the displacement of a key, the pulse which will come through to the grid of the tube forming stage 10 when the gate G_2 is unblocked will be unable to fire this tube.

From the moment that the gates G_1 and G_2 are unblocked, the counters CT_1 and CT_2 will both be driven by the pulses at terminal P_1 . In the case where $F_{i-1}+a_i \neq 11$, a state of affairs, as defined by the fourth row of the table, will be attained when CT_1 reaches condition 0. BS_1 will move to the 0-condition, G_3 and G_8 will be blocked, G_4 and G_5 will be unblocked. At this moment CT_2 is in condition $(F_{i-1}+a_i) \pmod{11}$, as can be easily verified.

From then on, pulses will continue to be applied from terminal P_1 to CT_2 , but CT_1 will be driven by the pulses from terminal P_2 through gates G_1 and G_4 in series. As these last pulses have twice the frequency of the former, conditions shown on the fifth row of the table will now be reached. Counter CT_2 reaches the 0-condition. This blocks the gate G_6 and thereby the gates G_1 and G_2 which means that the counters are no longer driven. Counter CT_1 is now in condition $2(F_{i-1}+a_i) \pmod{11}$.

Apart from counter CT_1 which has moved from condition F_{i-1} to condition $2(F_{i-1}+a_i) \pmod{11}$, the circuit is back to the initial conditions expressed on the first row of the table and the next digit can be keyed or the shift key can be operated to permit the keying of the next number. BS_4 is left in its 1-condition which permitted CT_2 to reach condition 0 due to the low potential at terminal P_1 having permitted the last tube of CT_2 to fire.

If $F_{i-1}+a_i=11$, instead of going from the condition of the third row of the table to those of the fourth, the condition defined in the eighth row will be reached, since CT_1 and CT_2 will simultaneously reach the 0-conditions and stay there, provided gate G_5 is unblocked with sufficient rapidity so that the gates G_6 , G_1 and G_2 are blocked before the next pulse at P_2 has an opportunity to drive CT_1 and CT_2 . Otherwise CT_2 would be driven a full cycle and CT_1 two full cycles and would then remain in their 0-conditions.

Supposing, for example, that F_{i-1} is equal to 3 and a_i is equal to 8, as in the case of keying the last digit (the proof digit) of the number 278498-8. Counter CT_1 will be brought to its 0-condition.

It is clear that the keying of every digit of an n -digit number will each time result in a similar modification of the condition of the CT_1 counter and the condition of the CT_1 counter after n digits have been keyed will be

$$\sum_{i=0}^{i=n-1} 2^{n-i} a_i \pmod{11}$$

e.g. 3 in the case of the number 278498. Then, the keying of the proof digit, e.g. 8, will bring CT_1 to the condition

$$\sum_{i=0}^{i=n} 2^{n+1-i} a_i \pmod{11}, \text{ e.g. 0}$$

The operation of the shift key will close contact "s," whereby the circuit conditions will now be as defined on the ninth row ($s=1$) of the table, i.e. unchanged with respect to those of the previous row, except that the O.K. signal will appear at the corresponding terminal from the 0-stage of CT_1 through the unblocked gate G_7 and the closed contact s . This "O.K." signal can be used in any desired manner to permit the keying of the next number.

In this respect reference can for example be made to the United States Patent No. 1,334,316.

If the shift key is depressed when counter CT_1 is not in its 0-condition, a state of affairs, as defined on the sixth row of the table, will be reached. Device BS_3 will be driven to its 0 condition by a pulse at terminal P_2 passing through the unblocked gate G_8 , the closed contact s' and the decoupling means R_a . Hence, gate G_7 will be blocked. Simultaneously, this and further pulses will be applied through the decoupling means R_b to the counter CT_1 which will be driven to its 0-condition for which gate G_8 will be blocked. These conditions are to be found on the seventh row of the table. Thus, despite the closure of contact "s," an "O.K." signal will not be delivered. The fact that BS_3 is in the 0-condition indicates a mistake and can be used in any desired manner to indicate to the operator that she should repeat her keying. The circuit is now ready for the repeated keying.

It will be observed that in the embodiment described, a value of $r=2$ has been chosen. This is, of course, not essential, but in the case where only a single source of pulses is available a frequency divided, such as BS_4 , or a frequency multiplier must be used, and these will generally be simpler when $r=2$. The frequency of the pulses will be chosen so that it is compatible with the keying speed. A frequency of 10 kc./s. for the pulses at terminal P_2 appears amply sufficient.

Some general considerations on whether a particular value of r will produce a group of $p-1$ distinct numbers from 1 to $p-1$, such as the group given by (10) where $r=6$ and $p=11$, can be given. If such a group is not produced, it means that there will be less than $p-1$ different b_i coefficients and not all single transpositions will be checked if the number of digits of the number (including the proof digit) is greater than the number of different coefficients. First of all it will be observed that the same coefficients may be obtained in one particular order from (8) or in the reverse order from

$$b_{i+1} \equiv r' b_i \pmod{p} \quad (17)$$

where r' is some other common ratio. Relations 8 and 17 immediately give the relation between r and r' as

$$rr' \equiv 1 \pmod{p} \quad (18)$$

i.e. r' is the inverse of r . When $p=11$ the various possible values of r each time paired with the inverse are given by

$$1 \times 1 \equiv 2 \times 6 \equiv 3 \times 4 \equiv 5 \times 9 \equiv 7 \times 8 \equiv 10 \times 10 \equiv 1 \pmod{11} \quad (19)$$

Thus, the group of coefficients given by (10) can be obtained with r equal to 2 or 6. A well known theorem states that

$$q^{p-1} \equiv 1 \pmod{p} \quad (20)$$

when p and q are integers, p is prime and q is not a multiple of p . Although p need not necessarily be prime for the purpose envisaged in this application, prime numbers such as 11, will nevertheless be advantageous,

as will be clear from the beginning of this description. When p ($p > 4$) is prime, $p-1$ can be decomposed into prime factors. If P_1 is any one of these factors, one can write

$$(q^{p_1}) \frac{p-1}{P_1} \equiv 1 \pmod{p} \quad (21)$$

Therefore, if r or r' is equal to q^{p_1} , only

$$\frac{p-1}{P_1}$$

different coefficients will be obtained, i.e. less than $p-1$.

Obviously, 1 and $p-1$ are unsuitable values for r , the last since

$$(p-1)^2 \equiv 1 \pmod{p} \quad (22)$$

Consequently, for $p=11$, values of 1, 3, 4, 5, 9 and 10 will not produce a group of $p-1$ different coefficients. Values of 2 or 6 and 7 or 8 are suitable in this respect. A value of 2 would still be suitable with $p=13$, since 2 and its inverse 7 are not exact powers. It would not be suitable with $p=17$, since its inverse 9 is a perfect square and 2 is a factor of 16. Of course, when the number of digits exceeds $p-1$ some transpositions cannot be checked, but these correspond to digits having $p-2$ digits between them and are the most unlikely. In any event a group of $p-1$ different coefficients is the most efficient solution.

It should be observed that the circuit shown includes only ten digit keys, which are used for the normal digits and for the proof digit, although there are eleven possible values for the proof digit. This is because the eleventh value for the proof digit is never used. Since the keying of a 0 is made to correspond to 10, whereas the keying of any other digit corresponds to the digital value keyed, this eleventh value which is not used is the 0. Therefore, all normal numbers which would require a "true 0" as a proof digit should not be used, since no sign is available for a "true zero." For example, the normal number 19 would require a "true zero" as a proof digit, since $2(1)+1(9)=11 \equiv 0 \pmod{11}$, and therefore cannot be used as such. However, the normal number 1 will require 9 as a proof digit and therefore, 19 will nevertheless be used, but as 1 followed by the proof digit 9. Such a scheme evidently cannot be applied when all numbers have to be used, e.g. numbers on which calculations are to be performed. But for numbers which represent a designation such as bank account numbers for example, a selection of the numbers to be used is permissible. On the other hand, the scheme has the great advantage that no extra symbol need be introduced and the proof digit is treated exactly as the others, no separation from the normal digits or special sign being necessary. By way of illustration, the first 45 decimal numbers which satisfy the relation

$$\sum_{i=0}^{i=n} 2^{n-i} a_i \pmod{11} \equiv 0 \quad (23)$$

are given below:

19	78	131	190	254	318	369	414	465
27	86	158	203	262	326	377	422	473
35	94	166	211	270	334	385	430	481
43	115	174	238	289	342	393	449	502
51	123	182	246	297	350	406	457	510

For all the numbers above, the last digit is always non-significant in so far as the designation conveyed by the number is concerned, but permits the checking of errors in transcription.

Evidently, when all numbers have to be used, an extra symbol should be made available for the eleventh proof digit. It may also happen that even with decimal numbers, an eleventh symbol is already used and available,

e.g. the decimal point. With eleven normal symbols, the circuit shown could still be used, key contacts for the eleventh symbol, e.g. the decimal point, being used to break the connection between P_3 and BS_2 , and that between stage 0 of counter CT_2 and the ten decoupling means such as R_0 and to drive BS_1 , BS_2 and BS_3 to the 1-condition when the eleventh symbol is keyed. In such a case, the number such as 267.4 would become 267.47 with the proof digit 7 on the extreme right and a wrong position of the decimal point would always be checked.

In general, with $p=11$, any error in transcription has 10 chances out of 11 to be detected. Any single wrong digit or any single transposition will always be detected if the number of digits forming a number is limited to 15 10. A skipped last digit will also be detected in all cases. Several consecutive digits which all suffer the same increase or decrease as a result of a transcription error, e.g. 234 becoming 345, will also be detected in all cases.

Although the proof digits to be initially associated 20 with the numbers can be easily calculated in any desired way, and for example in the case of bank account numbers there would be no difficulty in tabulating the account numbers, as shown partially above, the circuit can be used for an automatic determination of the proof 25 digit. It is merely necessary for the operator to key the significant part of the number and by applying a suitable potential at terminal P_4 , one of the lamps L will be lit, indicating the value of the proof digit, e.g. if counter CT_1 has been left with the stage 7 "on," lamp 30 L_4 which is connected between terminal P_4 and a suitable point of stage 7 will glow. The operator can then further key the proof digit, e.g. 4, to bring CT_1 to the 0-condition and press the shift key to continue with the determination of the proof digit for the next number. 35 In so doing, if the operator keys an incorrect proof digit this will be detected in the manner previously explained, so that an incorrect proof digit can never be assigned.

The embodiment shown carries the computation by 40 means of counters on a dynamic basis as formula 16 is particularly well adapted to such a computation. Although reference has been made to counters using cold cathode tubes, and to a particular type of these, this is merely an example and other types of counters including electro-mechanical counters could also be used. 45 Electro-mechanical counters should however be fast enough for the purpose and the use of step-by-step switches for instance, would be dependent on the keying speed desired and on the value of p .

It will therefore be appreciated that the figure shown 50 can be realized in a multiplicity of ways, the bi-stable circuits for example can be realized electronically as Eccles-Jordan circuits using vacuum or gas tubes, with electro-magnetic relays, or in any desired and suitable manner. Such details as the polarity of the pulses, the 55 eventual need for pulse inverters, capacitive or D.C. couplings, and shaping circuits have not been particularly mentioned, since they depend on the various elements which the designer will wish to combine in accordance with his requirements and facilities and in the manner 60 in which these will be best used, e.g. anode or cathode outputs for vacuum tube circuits. It will be appreciated for example that the two-condition device BS_2 permits the avoidance of the undesirable effects which contact vibrations, e.g. k_0 , would have on the state of the gates 65 such as G_1 . If contact arrangements can be designed in such a way that no vibrations occur, then a trigger device such as BS_2 becomes redundant.

Finally, how the various numbers, such as bank 70 account numbers, are recorded has not been shown or described, as this has no particular bearing on the invention which relates to means for preventing errors in transcription. However, the checking arrangement shown could well be operated from the actually recorded numbers, so as to verify machine errors as well.

11

While the principles of the invention have been described above in connection with specific apparatus, it is to be clearly understood that this description is made only by way of example and not as a limitation on the scope of the invention.

I claim:

1. Calculating means to calculate a function

$$F = \sum_{i=0}^{i=n} b_i a_i \pmod{p}$$

where $a_i (0 \leq i \leq n)$ is one of a set of associated numerical symbols, $n+1$, the number of symbols, p , a predetermined integer, and $b_i (0 \leq i \leq n)$, one of a group of integer coefficient such that $b_i \equiv r b_i + 1 \pmod{p}$ where r is a predetermined integer, comprising an electrical ring counter with p stable conditions, a second ring counter with p stable conditions, a first pulse source, a second pulse source having r times the frequency of said first source, means for successively setting said second ring counter in a condition a_i corresponding to a numerical symbol and said first ring counter in a condition F_{i-1} , means responsive to the release of said setting means for driving said first and second counters by said first pulse source until they respectively pass through the condition 0 and $(F_{i-1} + a_i) \pmod{p}$, a two-condition device, means responsive to said first counter reaching said 0-condition for causing said two-condition device to be displaced from its first to its second condition, means responsive to said two-condition device being in its second condition for causing said second pulse source to drive said first counter while said second counter remains driven by said first pulse source until said first and second counters respectively reach their $r (F_{i-1} + a_i) \pmod{p}$ and 0 conditions, and means responsive to said first and second count-

12

ers reaching said last-named condition, in conjunction with said two-condition device being in its second condition, for causing the disconnection of said pulse sources from said counters, whereby said counters remain in the condition attained.

5 2. Calculating means comprising a first ring counter and a second ring counter each having a predetermined plurality of stable conditions, selective means for setting said second counter in a desired condition corresponding to a numerical symbol, means responsive to the release of said setting means for causing both said counters to step successively from one stable condition to the next stable condition until said first counter reaches a predetermined particular stable condition, means responsive to said first counter reaching said particular stable condition for thereafter altering said stepping means to cause said first counter to step successively from one stable condition to the next at a rate which is a predetermined multiple of the rate at which said second counter is stepped, means responsive to said altering means for thereafter stopping both said counters when said second counter reaches a predetermined particular stable condition, and means for indicating whether or not said first counter has stopped on said particular stable condition.

10 20 25 3. Calculating means, as claimed in claim 2, further comprising means for indicating at which stable condition the first counter has stopped.
